METAL FLOORING SECTION FOR ANIMAL ENCLOSURES AND THE LIKE

Grant T. Facer, Lafayette, and John A. Metzger, Fresno, Calif., assignors to Kaiser Aluminum & Chemical Corporation, Oakland, Calif.

Filed Sept. 14, 1972, Ser. No. 289,151

Term of patent 14 years

Int. Cl. D25—02

U.S. Cl. D13—1 J

FIG. 1

FIG. 2

FIG. 5

FIG. 3

FIG. 4

FIG. 1 is a perspective view of the flooring section of our invention that is provided with a reoccurring top surface pattern and can be elongated;

FIG. 2 is a top plan view of the flooring section shown in FIG. 1;

FIG. 3 is a side elevational view of the flooring section shown in FIG. 1;

FIG. 4 is an end view of the flooring section shown in FIG. 1; and

FIG. 5 is a bottom plan view of the flooring section shown in FIG. 1.

We claim:

The ornamental design for a metal flooring section for animal enclosures and the like, substantially as shown and described.
